(57) **CLAIM**

The ornamental design for a display screen with graphical user interface, as shown and described.

DESCRIPTION

FIG. 1 illustrates a front view of a display screen portion of a graphical user interface depicting an image displayed thereof; and,

FIG. 2 illustrates a front view of a display screen portion of a graphical user interface depicting an alternate embodiment of an image displayed thereof.

The outermost broken lines showing a portion of an electronic device illustrate environment subject matter, whereas the dot-dot-dash broken lines showing a display screen and evenly spaced broken lines within showing elements of the graphical user interface illustrate portions of the article. None of the broken lines form part of the claimed design.
